UNITED STATES PATENT OFFICE.

WALTER KAHLE, OF ERFURT, GERMANY, ASSIGNOR TO A E G DEUTSCHE WERKE AKTIEN-GESELLSCHAFT, OF BERLIN, GERMANY.

TYPEWRITER.

Application filed July 18, 1924. Serial No. 726,765.

To all whom it may concern:

Be it known that I, WALTER KAHLE, a citizen of Germany, residing at Erfurt, Germany, have invented certain new and useful 5 Improvements in Typewriters, of which the following is a specification.

My invention relates to typewriters and more especially to that class of typewriters in which the paper carriage is wider than in 10 typewriters of the usual type, the object being to permit the use of extra wide sheets. As such machines are required only in exceptional cases and therefore do not pay in view of their high initial cost, it has been 15 proposed to provide the main frame of normal width with an exchangeable upper part which can be exchanged for a wider part adapted to support a wider carriage.

This solution, however, is not satisfactory 20 as it necessitates a specially constructed main frame.

It is an object of my invention to provide a typewriter of the class described with means for writing extra long lines notwithstanding the fact that its main frame is of 25 normal width. To this end I provide the machine with an auxiliary frame for extending the normal carriage guides which may be screwed or secured to the normal main frame by snap bolts or any other suitable means. The auxiliary frame is preferably designed 30 to form a self-contained unit comprising a track for the roll of the wide carriage and two lateral extensions of the carriage rail.

35 In the drawings affixed to this specification and forming part thereof a device embodying my invention is illustrated diagrammatically by way of example. In the drawings—

40 Fig. 1 is plan view of my auxiliary frame.

Fig. 2 is a diagrammatic plan view of the main frame showing the auxiliary frame in position thereon in dotted lines.

45 Fig. 3 is an end elevation of the main frame and fittings, partly in section on the line A—B in Fig. 2.

Referring to the drawings, the auxiliary frame comprises a track *b* for guiding the roll *a* of the long carriage *a'* and two extension rails *c*, *c'*. As will be seen in Fig. 2, the normal rail *d* of the main frame *g* fits exactly between the two auxiliary rails *c*, *c'*, so that a continuous rail is formed when the extension rails *c*, *c'* are in position on which

the wider carriage may be placed. The auxiliary frame is provided with lugs *f*, *f* supporting set screws *e*, *e* at both sides and a set screw *e'* at the rear by which it may be secured to the main frame *g* of the machine and dowel pins *i*, *i'* formed on lugs *h*, *h'* and adapted to fit into holes *j*, *j'* in the main frame. By these means the auxiliary frame is secured to the main frame and its extension rails *c*, *c'* are properly connected with the fixed rail *d*.

65 The auxiliary frame comprising the track and auxiliary shift rails may be divided instead of being made in one, as shown. In this case, each part supports one of the extension rails and one half of the track. The two parts are secured to the frame of the machine and the track and rail form a complete unit. Such and other combinations and modifications may be made without departing from the spirit of my invention.

70 I wish it to be understood that I do not desire to be limited to the exact details of construction shown and described, for obvious modifications will occur to a person skilled in the art.

75 I claim:—

1. A typewriter comprising a main track to support the carriage and lateral extensions adapted to be temporarily secured to the end of said track so as to form a continuation thereof.

80 2. A typewriter comprising a main frame, a rear track and a front guide rail forming part of said frame and an auxiliary frame adapted to be temporarily secured to the machine and forming a lateral extension of both said rear track and said front guide rail.

85 3. A typewriter comprising a main frame, a rear track and a front guide rail forming part of said frame and a substantially U-shaped auxiliary frame adapted to be temporarily secured to the machine and forming a lateral extension of both said rear track and said front guide rail.

90 4. A removable extension track for typewriter carriages comprising a rear track rail of greater width than the normal carriage support and front extension rails secured to the ends of said track rail in parallel therewith.

100 5. A removable extension track for typewriter carriages comprising a rear track rail or greater width than the normal carriage

support, front extension rails secured to the ends of said track rail in parallel therewith and means for removably fixing said extension track to the typewriter frame.

5. 6. A typewriter comprising a main frame to support the carriage, a rear track and a front rail forming part of said frame, an

auxiliary frame adapted to be temporarily secured to said main frame so as to form a lateral extension of both said rear track and front rail and means for removably fixing said auxiliary frame to said front rail.

In testimony whereof I affix my signature.
WALTER KAHLE.
